UNITED STATES PATENT OFFICE.

BERTINIUS LARSEN, OF NILES, MICHIGAN, ASSIGNOR TO NATIONAL STANDARD COMPANY, OF NILES, MICHIGAN.

LIFTING-JACK.

1,135,299.

Specification of Letters Patent.

Patented Apr. 13, 1915.

Application filed October 26, 1914. Serial No. 868,624.

To all whom it may concern:

Be it known that I, BERTINIUS LARSEN, a citizen of the United States, residing at Niles, Michigan, have invented certain new and useful Improvements in Lifting-Jacks, of which the following is a specification.

This invention relates to improvements in lifting jacks.

The main objects of this invention are: 10 First, to provide an improved gear lifting jack which is powerful and at the same time of compact structure and well adapted for small jacks such as automobile jacks. Second, to provide in a lifting jack an improved reversing mechanism.

Further objects, and objects relating to structural details, will definitely appear from the detailed description to follow.

I accomplish the objects of my invention 20 by the devices and means described in the following specification.

The invention is clearly defined and pointed out in the claims.

A structure which is a preferred embodiment of my invention is clearly illustrated in the accompanying drawing forming a part of this specification, in which:

Figure I is a front perspective view of a structure embodying the features of my invention. Fig. II is a detail side view looking from the left of Fig. I with the side plate 37 of the housing 34 removed, the reversing member being locked in its inoperative position. Fig. III is a similar view 35 with the reversing member and the reversing plate locking lever removed. Fig. IV is a detail side view of the opposite or right hand side of the jack with the side plate 13 of the housing 12 removed. Fig. V is a de-

tail view partially in vertical section on a line corresponding to line 5—5 of Fig. VI. Fig. VI is a detail vertical section on a line corresponding to line 6—6 of Fig. III. Fig. VII is a detail side view looking from the left of Fig. I with the side plate 37 removed, the reversing member being shown 40 in its operative position, the lever and co-acting parts being shown by full lines in the position occupied when the lever is in its lower position, and by dotted lines when the lever is in its upper or raised position.

In the drawing, similar reference numerals refer to similar parts throughout the several views, and the sectional views are

taken looking in the direction of the little 55 arrows at the ends of the section lines.

Referring to the drawing, the standard or frame 1 is provided with a suitable base 2. The standard is adapted to receive the lifting bar 3 which is provided with a rack 4 on one side. The lifting bar is provided with a head 5, the head being provided with a step 6.

The actuating shaft 7 is mounted in the frame transversely of the rack and is provided with a pinion 8 meshing with a gear 9 on the shaft 10 which is also disposed transversely of the rack and provided with a pinion 11 meshing with the rack. The gears 8 and 9 are arranged in a housing 12 65 having a removable face plate 13. On the actuating shaft 7 is a ratchet wheel 14. The actuating lever 15 is pivoted on the shaft 7, it being disposed between the ratchet wheel and the frame. The actuating pawl 16 is 70 pivoted on the lever at 17 to coact with the ratchet, the pawl facing upwardly as shown in the drawing. The pawl is provided with a spring 18. A holding pawl 19 is arranged above the ratchet wheel, that is, it is arranged oppositely to the actuating pawl. The pawl 19 is mounted on a projecting stud 20 on the frame and is provided with a spring 21 carried by the stud 22 projecting from the frame above the stud 20. The 75 pawls are provided with laterally projecting pins 23 adapted to coact with the reversing plate or member 24. The reversing member 24 is pivoted on the shaft 7 on the outer side of the ratchet wheel. The reversing member is actuated by the U-shaped spring 25 one arm of which is mounted on the stud 26 projecting from the frame its other arm bearing on the rear edge of the reversing member. The reversing member 80 is provided with a cam 27 on its upper edge adapted to act on the pin of the holding pawl and with a cam 28 on its lower edge adapted to act on the pin of the actuating pawl. The reversing member has upwardly 85 projecting fingers 29 and 30 one at each end of its cam 27. The reversing member is held in its inoperative position by the cam lever 31 which is pivoted at 32 to project through a slot 33 in the housing 34. The 90 lever has a notch 35 which engages with the upper end of the finger 29 when the actuating member is in its rear or inoperative po-

100
105
110

sition, as shown in Fig. II, it being carried to its inoperative position by the cam 36 on the lever. The finger 29 serves as a stop for limiting the forward movement of the reversing member, see Fig. VII.

With the reversing member in its inoperative position as shown in Fig. II the reciprocation of the lever 15 will, through the pawl and ratchet and gear connections described, raise the lifting bar. When it is desired to lower the lifting bar the lever 31 is thrown into the position shown in Fig. VII which releases the reversing member so that as soon as the holding pawl is relieved of its load the reversing member swings forward to the position shown in Fig. VII, lifting the holding pawl from the rack. The upward or lowering stroke of the lever brings the pin of the actuating pawl into contact with the cam 28 rocking the reversing member rearwardly until the holding pawl drops into engagement with the ratchet as shown by dotted lines in Fig. VII. As soon as the load is released from the actuating pawl the tension of the spring 25 acting on the reversing plate throws the same forward and the tension of the pawl spring 18 disengages the actuating pawl and holds it from engagement with the ratchet during the return stroke of the lever. As the lever reaches the end of its down stroke the reversing member permits the reengagement of the actuating pawl and as soon as the holding pawl is relieved of its load the reversing plate disengages it and the action may be repeated, the movement being a step by step movement. The housing 34 is provided with a removable face plate 37 which affords full access to the parts.

My improved lifting jack is very powerful and at the same time is compact so that it is well adapted for use as an automobile jack. The jack may be adapted for raising or lowering as desired merely by the shifting of the lever 31.

I have not attempted to illustrate or describe certain modifications which I contemplate as I believe the disclosure made will enable those skilled in the art to which my invention relates to embody or adapt the same as conditions may require. I desire however, to be understood as claiming my improvements specifically in the form illustrated as well as broadly within the scope of the appended claims.

Having thus described my invention, what I claim as new and desire to secure by Letters Patent, is:

1. In a lifting jack the combination with the frame, of a lifting bar having a rack thereon, a shaft, driving connections for said shaft to said rack including a pinion meshing with said rack, a ratchet wheel on said shaft, an actuating lever pivotally mounted on said shaft on the inner side of

said ratchet wheel, an actuating pawl on said lever coacting with the under side of said ratchet wheel, a holding pawl on said frame disposed above and coacting with the upper side of said ratchet wheel, said pawls having outwardly projecting pins thereon, springs for said pawls, a reversing member pivotally mounted on said shaft on the outer side of said ratchet wheel and having a pair of spaced fingers on its upper edge with a cam between coacting with the pin on said holding pawl, and a cam on its under edge coacting with said pin on said actuating pawl, a spring acting on said reversing member, and a cam lever for shifting said reversing member to and retaining it in its inoperative position, said lever having a notch therein adapted to receive one of the fingers of said reversing member when shifted to inoperative position by said cam lever.

2. In a lifting jack the combination with the frame, of a lifting bar having a rack thereon, a shaft, driving connections for said shaft to said rack including a pinion meshing with said rack, a ratchet wheel on said shaft, an actuating lever pivotally mounted on said shaft on the inner side of said ratchet wheel, an actuating pawl on said lever coacting with the under side of said ratchet wheel, a holding pawl on said frame disposed above and coacting with the upper side of said ratchet wheel, said pawls having outwardly projecting pins thereon, springs for said pawls, a reversing member pivotally mounted on said shaft on the outer side of said ratchet wheel and having a cam on its upper edge coacting with the pin on said holding pawl, and a cam on its under edge coacting with said pin on said actuating pawl, a spring acting on said reversing member, and means for holding said reversing member in its inoperative position.

3. In a lifting jack the combination with the frame, of a lifting bar having a rack thereon, a shaft, driving connections for said shaft to said rack including a pinion meshing with said rack, a ratchet wheel on said shaft, an actuating lever pivotally mounted on said shaft on the inner side of said ratchet wheel, an actuating pawl on said lever coacting with said ratchet wheel, a holding pawl disposed oppositely to said actuating pawl, springs for said pawls, a reversing member pivotally mounted on said shaft on the outer side of said ratchet wheel to coact with both of said pawls whereby they are alternately engaged and disengaged, a spring action on said reversing member, and means for retaining said reversing member in its inoperative position.

4. In a lifting jack, the combination of an actuating shaft, a ratchet wheel on said shaft, an actuating lever pivotally mounted on said shaft, an actuating pawl on said lever coacting with the under side of said

ratchet wheel, a holding pawl disposed above and coacting with the upper side of said ratchet wheel, said pawls having outwardly projecting pins thereon, springs for 5 said pawls, a reversing member pivotally mounted on said shaft and having a cam on its upper edge and stops at the end of said cam coacting with the pin on said holding pawl, and a cam on its under edge coacting 10 with said pin on said actuating pawl, a spring acting on said reversing member, and means for shifting said reversing member to and retaining it in its inoperative position.

15 5. In a lifting jack, the combination of an actuating shaft, a ratchet wheel on said shaft, an actuating lever pivotally mounted on said shaft, an actuating pawl on said lever coacting with said ratchet wheel, a 20 holding pawl disposed oppositely to said actuating pawl, springs for said pawls, a spring actuated reversing member pivotally mounted on said shaft to coact with both of 25 said pawls, and means for retaining said actuating member in its inoperative position.

6. In a lifting jack, the combination of an actuating shaft, a ratchet wheel on said shaft, an actuating lever pivotally mounted 30 on said shaft, an actuating pawl on said lever coacting with said ratchet wheel, a holding pawl disposed oppositely to said actuating pawl, springs for said pawls, a spring actuated reversing member pivotally 35 mounted on said shaft and disposed between said pawls to swing forward and disengage said holding pawl when said pawl is relieved of its load, said reversing plate being engaged by the actuating pawl on the lowering 40 stroke of the lever and actuated against its spring to permit the engagement of said holding pawl, said actuating pawl being disengaged on being relieved of its load, by said reversing member, and being held thereby from engagement with said ratchet during the return stroke of the lever, and means for retaining said reversing member in its inoperative position.

45 7. In a lifting jack, the combination of an

actuating shaft, a ratchet wheel on said 50 shaft, an actuating lever pivotally mounted on said shaft, an actuating pawl on said lever coacting with said ratchet wheel, a holding pawl, springs for said pawls, a spring actuated reversing member pivotally 55 mounted on said shaft and arranged to swing forward and disengage said holding pawl when said pawl is relieved of its load, said reversing plate being engaged by the actuating pawl on the lowering stroke of 60 the lever and actuated against its spring to permit the engagement of said holding pawl, said actuating pawl being disengaged on being relieved of its load, by said reversing member, and being held thereby from 65 engagement with said ratchet during the return stroke of the lever, and means for retaining said reversing member in its inoperative position.

8. In a lifting jack, the combination of an 70 actuating ratchet wheel, an actuating lever, an actuating pawl on said lever coacting with said ratchet wheel, a holding pawl disposed oppositely to said actuating pawl, springs for said pawls, a spring actuated 75 pivotally mounted reversing member disposed between said pawls to swing forward and disengage said holding pawl when said pawl is relieved of its load, said reversing plate being engaged by the actuating pawl 80 on the lowering stroke of the lever and actuated against its spring to permit the reengagement of said holding pawl, said actuating pawl being disengaged on being relieved of its load, by said reversing member, 85 and being held thereby from reengagement with said ratchet during the return stroke of the lever, and means for retaining said reversing member in its inoperative position.

90 In witness whereof, I have hereunto set my hand and seal in the presence of two witnesses.
